UNITED STATES PATENT OFFICE.

DUDLEY JAMES BARNARD, OF BARKING, ENGLAND.

GRAB.

Application filed November 4, 1924. Serial No. 747,851.

This invention relates to improvements in grabs of the type in which all movements of the grab are effected by a single chain or rope and in particular to grabs designed for use with transporters and it has for its object the provision of improved mechanism for preventing the opening of the bucket sections due to the removal of the load from the hauling chain while the grab is being transported from one point to another.

In the specification to a prior patent (No. 1,477,530) granted to me, a form of mechanism is described comprising a vertically disposed gravity catch pivoted to one of the top bar plates said catch being adapted to engage with a toothed member provided on the sheave block plate on the same side; the lower end of the gravity catch being arranged to coact with the locking latch. It has been found in practice that when, as frequently happens when handling material of large size, the bucket sections are prevented from closing, the vertically disposed gravity catch binds on the toothed member and prevents the separation of the two parts when the grab is dumped.

It is proposed to overcome this difficulty according to the present invention by mounting the vertically disposed gravity catch on that part of the grab located at the head thereof adapted to engage the carriage of the transporter or like device and to provide a pin or like part on the sheave block plate or on a part carried thereby said pin being so located in relation to the hook on the gravity catch that said parts only come into operation while the grab is being supported by the transporter carriage but fall free from each other when the grab is supported on the hauling chain.

In the accompanying drawings which illustrate one embodiment of this invention:—

Figure 1 is a side elevation showing the operative parts of the grab in the position they occupy when the grab is closed and supported by the hauling chain.

Figures 2 and 3 are views in side and front elevation respectively on an enlarged scale illustrating details of the locking mechanism; and,

Figure 4 is a similar view to Figure 2

showing the position of the locking mechanism when the grab is closed and supported by the transporter carriage.

In the drawings 1 and 2 are the bucket sections pivoted on independent pins 3 and 4 on a cross beam 5. 6 and 7 are the top cross bars and 8 the spreader arms, one being arranged at each corner of the bucket sections. The means for maintaining the normal balance of the operative parts of the grab consist of two vertically disposed telescopic devices arranged one on each side of the sheave blocks, one member 9 of each device being secured to the cross-beam 5 the other member 10 being arranged to slide thereon and in a bracket 11 secured to the lower sheave block plate 12 springs 13 being provided to take up the shock when the part 10 comes to the limits of its movements.

The locking mechanism which forms the subject of the present invention comprises a gravity catch pivoted at 14 to the plate 12 of the lower sheave block, said gravity catch comprising a hooked member 15 adapted to coact and engage with a pin 16 carried by the cross-beam 5, a horizontally disposed weighted member 17 and an upwardly extending member 18 provided at its upper end with a pin 19 adapted to coact with and to be engaged by a hooked member 20 pivoted on one of the legs of a vertically disposed member 21 the upper end of which constitutes the member adapted to be engaged by the carriage provided on the transporter or the like device and carries the entire load during the period of transportation.

The member 21, as more clearly shown in Figure 3 is forked at its lower end, the legs of said member being arranged to straddle the plates 22 of the upper sheave block each of said legs being arranged to slide between guides 23.

For the purpose of maintaining the hooked member 15 of the gravity catch in its operative position a pin or projection 24 is provided on the inner face of the weighted member 17 adapted to be engaged by a plate 25 carried by a vertically disposed rod 26 slidably mounted in brackets 27 secured to the sheave block plate 12. The upper end of

the rod 26 is arranged to coact with a part 28 secured to the plate 22 of the upper sheave block.

- In operation, assuming the grab to be supported by the hauling chain 31 as shown in Figures 2 and 3, the free end of such chain being secured to a fixed part of the grab, for example, to the stud 32 provided on the block plate 22, the weight of the grab is supported by the hooked member 15 engaging with the pin 16 and if the grab is dumped and the chain 31 slackened the weighted member 17 will cause the hook to disengage itself automatically from said pin 16 and fall clear of the hook 20. On the chain 31 being hauled in and the grab raised the bucket sections will fall apart. This automatic disengagement on dumping is permitted by reason of the fact that the load is removed from the hook 15 and that the plate 25 is, as shown in Figure 3, out of engagement with the pin 24. Immediately the lower sheave block is lowered away from the upper sheave block the rod 26 is forced upwardly by the spring 29 so as to bring the plate 25 against the pin 24 and when the hook 15 is again lowered into contact with the pin 16 the plate 25 and rod 26 are depressed against the action of the spring 29 and the hook is then drawn under the pin 16 and is maintained in this position by the plate 25.

When it is desired to transport the grab to another position the transporter carriage is caused to engage with the member 21, and the hauling chain 31 is slackened thereby causing the grab to fall slightly into the position shown in Figure 4 so as to bring the hook 20 into engagement with the pin 19 on the member 18 and the enlarged parts 30 on the lower ends of the legs of the member 21 into engagement with the lower ends of the guides 23, the entire weight of the grab being now taken by the transporter carriage through the member 21. By this means the hooked member 15 of the gravity catch is maintained in its locked position. Immediately the member 21 is released from the transporter carriage and the load is supported by the chain the member 21 drops into its lowest position and frees the hook 20 from the pin 19.

I claim:—

1. In a grab of the type described provided with means connecting the cross-beam carrying the bucket sections and movable sheave block, the combination of means comprising a pin on the cross-beam, a gravity catch pivoted on the lower sheave block, guide members on the side plates of the upper sheave block, means slidably mounted in said guide members adapted to coact with the travelling carriage of a transporter, a vertically disposed hook shaped member pivoted on said means adapted to coact with the gravity catch and to hold said catch in engagement with the pin on the cross-beam when the grab is supported by the transporter carriage.

2. In a grab of the type described provided with means connecting the cross-beam carrying the bucket sections and movable sheave block, the combination of means comprising a pin on the cross-beam, a gravity catch pivoted on the lower sheave block, 70 guide members on the side plates of the upper sheave block, means mounted in said guide members adapted to coact with the travelling carriage of a transporter, a hook shaped member pivoted on said means adapted to coact with the gravity catch and to hold said catch in engagement with the pin on the cross-beam when the grab is supported by the transporter carriage.

2. In a grab of the type described provided with means connecting the cross-beam carrying the bucket sections and movable sheave block, the combination of means comprising a pin on the cross-beam, a gravity catch pivoted on the lower sheave block, 75 guide members on the side plates of the upper sheave block, means mounted in said guide members adapted to coact with the travelling carriage of a transporter, a hook shaped member pivoted on said means adapted to coact with the gravity catch and to hold said catch in engagement with the pin on the cross-beam when the grab is supported by the transporter carriage, and spring controlled means on the movable 80 sheave block adapted to coact with and control the position of the gravity catch.

3. In a grab of the type described provided with means connecting the cross-beam carrying the bucket sections and movable sheave block, the combination of means comprising a pin on the cross-beam, a gravity catch comprising a vertically disposed hook shaped member, a horizontally disposed weighted member and a vertically disposed 85 pin carrying member pivoted on the lower sheave block, guide members on the side plates of the upper sheave block, means slidably mounted in said guide members adapted to coact with the travelling carriage of a transporter, and a vertically disposed hook shaped member pivoted on said means adapted to coact with the pin carrying member of the gravity catch and to hold the hook shaped member of the gravity catch in engagement with the pin on the cross-beam when the grab is supported by the transporter carriage. 100

4. In a grab of the type described provided with means connecting the cross-beam carrying the bucket sections and movable sheave block, the combination of means comprising a pin on the cross-beam, a gravity catch comprising a vertically disposed hook shaped member, a horizontally disposed 105 weighted member and a vertically disposed pin carrying member pivoted on the lower sheave block, guide members on the side plates of the upper sheave block, means slidably mounted in said guide members adapted to coact with the travelling carriage of a transporter, a vertically disposed hook shaped member pivoted on said means adapted to coact with the pin carrying member of the gravity catch and to hold the hook-shaped member of the gravity catch in engagement with the pin on the cross-beam when the grab is supported by the transporter carriage. 110

to coact with the weighted member of the gravity catch to control the position of said gravity catch.

5. In a grab of the single chain type provided with means connecting the cross-beam carrying the bucket sections and movable sheave block, the combination of means comprising a pin on the cross-beam, a gravity catch pivoted on the lower sheave block, 10 guide members on the side plates of the upper sheave block, means adapted to coact with the travelling carriage of a transporter comprising a member provided with two legs slidably mounted in said guide members, means on the lower ends of said legs adapted to limit the sliding movement of said member, and a vertically disposed hook shaped member pivoted on one of the legs of said member adapted to coact with the 15 gravity catch and to hold said catch in engagement with the pin on the cross-beam when the grab is supported by the transporter carriage.

6. In a grab of the type described provided with means connecting the cross-beam carrying the bucket sections and movable sheave block, the combination of means comprising a pin on the cross-beam, a gravity catch pivoted on the lower sheave block, 20 guide members on the side plates of the upper sheave block, means adapted to coact with the travelling carriage of a transporter comprising a fork-shaped member adapted to straddle the plates of the upper sheave block and slidably mounted in said guide members enlargements on the ends of the legs of said fork-shaped member adapted to engage with the lower ends of the guide members, and a vertically disposed hook shaped member pivoted on said fork-shaped member adapted to coact with the gravity catch and to hold said catch in engagement with the pin on the cross-beam when the 25 grab is supported by the transporter carriage.

7. In a grab of the type described provided with means connecting the cross-beam carrying the bucket sections and movable sheave block, the combination of means comprising a pin on the cross-beam, a gravity catch comprising a vertically disposed hook shaped member, a horizontally disposed weighted member and a vertically disposed pin carrying member pivoted on the lower 30 sheave block, guide members on the side plates of the upper sheave block, means adapted to coact with the travelling carriage of a transporter comprising a fork-shaped member adapted to straddle the plates of the upper sheave block and slidably mounted in said guide members enlargements on the ends of the legs of said fork-shaped member adapted to engage with the lower ends of the guide members, a vertically disposed hook shaped member pivoted

on one of the legs of said fork-shaped member adapted to coact with the pin carrying member of the gravity catch and to hold the hook-shaped member of the gravity catch in engagement with the pin on the cross-beam when the grab is supported by the transporter carriage, and spring controlled means on the movable sheave block adapted to coact with the weighted member of the gravity catch to control the position of said gravity catch. 70

8. In a grab of the single chain type the combination with means for maintaining the normal balance of the operative parts of the grab, comprising two vertically disposed telescopic devices arranged one on each side of the sheave blocks, of means connecting the cross-beam carrying the bucket sections and movable sheave block, comprising a pin on the cross-beam, a gravity catch pivoted 80 on the lower sheave block, guide members on the side plates of the upper sheave block, means slidably mounted in said guide members adapted to coact with the travelling carriage of a transporter, a vertically disposed hook shaped member pivoted on said means adapted to coact with the gravity catch and to hold said catch in engagement with the pin on the cross-beam when the grab is supported by the transporter carriage, and spring controlled means on the movable sheave block adapted to coact with the gravity catch. 85

9. In a grab of the single chain type the combination with means for maintaining 100 the normal balance of the operative parts of the grab, comprising two vertically disposed telescopic devices arranged one on each side of the sheave blocks of means connecting the cross-beam carrying the bucket sections and movable sheave block, comprising a pin on the cross-beam, a gravity catch comprising a vertically disposed hook-shaped member, a horizontally disposed weighted member and a vertically disposed pin carrying member pivoted on the lower sheave block, guide members on the side plates of the upper sheave block, means adapted to coact with the travelling carriage of a transporter comprising a fork-shaped member 105 adapted to straddle the plates of the upper sheave block and slidably mounted in said guide members, enlargements on the lower ends of the legs of said fork-shaped member adapted to engage with the lower ends of the guide members, a vertically disposed hook shaped member pivoted on said fork-shaped member adapted to coact with the pin carrying member of the gravity catch and to hold the hook-shaped member of the gravity catch in engagement with the pin on the cross-beam when the grab is supported by the transporter carriage, and spring controlled means on the movable sheave block adapted to coact with the weighted 110

member of the gravity catch. 115

120

125

130

member of the gravity catch to control the position of said gravity catch.

10. In a grab of the single chain type the combination of means for connecting the cross-beam carrying the bucket sections and movable sheave block comprising a pin on the cross-beam, a gravity catch pivoted on the lower sheave block, a pin carried by said gravity catch, guide members on the

side plates of the upper sheave block, means ¹⁰ slidably mounted in said guide members adapted to coact with the travelling carriage of a transporter, means pivoted on said slide-
able means adapted to coact with the pin on the gravity catch and means on the mov-
able sheave block adapted to coact with and control the position of said gravity catch. ¹⁵

DUDLEY JAMES BARNARD.
